COMBINED DISPLAY CARD AND STAMP PACKAGE

Eurith Dickerson Williams, Box 110,
Atlanta, Ga. 30301

Filed Sept. 23, 1974, Ser. No. 508,034

Term of patent 14 years

Int. Cl. D9—03

U.S. Cl. D9—191

FIG. 1

FIG. 2

FIG. 3

FIG. 4

FIG. 5

FIG. 6

FIG. 1 is a perspective view of a combined display card and stamp package showing my new design;

FIG. 2 is a front elevational view;

FIG. 3 is a rear elevational view;

FIG. 4 is a side elevational view, the opposite side being the same in appearance;

FIG. 5 is a top plan view; and

FIG. 6 is a bottom plan view thereof.

The side not shown is similar to the shown side.

I claim:

The ornamental design for a combined display card and stamp package, substantially as shown and described.
